Application July 22, 1952, Serial No. 20,720

Term of patent 14 years

(Cl. D7—7)

To all whom it may concern:

Be it known that I, Salvatore Ferragamo, a citizen of Italy, residing at the Town of Firenze, in the Country of Italy, have invented a new, original, and ornamental Design for a Shoe, of which the following is a specification, reference being had to the accompanying drawings, forming part thereof.

In the drawing

Fig. 1 is a top plan view of the shoe, showing my new design;

Fig. 2 is a side view;

Fig. 3 is a bottom plan view;

Fig. 4 is a perspective view of the bottom of the shoe.

The characteristic feature of my design for a shoe resides in the configuration of the heel where it joins the upper in association with that portion of the vamp between the heel and the sole.

I claim:

The ornamental design for a shoe, substantially as shown, and described.

SALVATORE FERRAGAMO.
